UNITED STATES PATENT OFFICE.

MORRIS ECKER, OF NEW YORK, N. Y., ASSIGNOR OF ONE-HALF TO LENA STERN, OF SAME PLACE.

ATTACHMENT FOR WINDOW-SHADES.

SPECIFICATION forming part of Letters Patent No. 624,766, dated May 9, 1899.

Application filed October 28, 1898. Serial No. 694,792. (No model.)

To all whom it may concern:

Be it known that I, MORRIS ECKER, a citizen of the Empire of Austria-Hungary, residing in the city of New York, borough of Manhattan, and State of New York, have invented 5 certain new and useful Improvements in Attachments for Window-Shades, of which the following is a specification.

This invention relates to an improved attachment for window-shades by which the shade-roller can be so adjusted as to be suspended higher or lower on the window-frame, so as to permit the admission of light in a more convenient manner than heretofore.

15 My invention consists of certain features of construction to be hereinafter described in detail and then pointed out in the claim.

In the accompanying drawings, Figure 1 represents the front elevation of a window with 20 my improved attachment to the shade-roller applied thereto. Fig. 2 is a perspective detail of the attachment, on a larger scale, broken out in the center. Figs. 3 and 4 are details in transverse sections through lines 25 3 3 and 4 4, respectively, of Fig. 2; and Figs. 5 and 6 are detail views of the two suspension-plates.

Similar letters of reference indicate corresponding parts.

30 Referring to the drawings, A represents two grooved guide-rails which are attached stationarily to the window-frame, preferably at the upper part of the same. The guide-rails A are of such length that they extend from 35 the top of the frame to some distance below the meeting-rails of the sashes. The guide-rails are preferably bent up, of suitable sheet metal or any other suitable material, and are supported by means of brackets *a a'*, that are 40 either made integral with the rails or riveted thereto at some distance from the sashes, so that the shade-roller can be freely wound on or unwound from its roller. The shade B' is mounted on a spring-roller B of any improved 45 construction, provided at the ends with the usual studs or gudgeons *b b'*, which extend into grooves of the guide-rails. The studs or gudgeons *b b'* are applied to suspension-plates D, of which one has a round opening *d* for the 50 round stud *b*, while the opposite suspension-plate has an oblong hole *d'* for the opposite flat stud *b'* of the shade-roller, by which the winding of the spring is effectuated in the well-known manner. The suspension-plates

are connected at their upper ends with cords 55 E, that are placed over pulleys *e* at the upper ends of the guide-rails, both cords passing over the pulley of one of the guide-rails and being connected with a chain or cord E', that is secured in position by a clamp F or other 60 fastening device applied to the window-frame. The lower end of the cord or chain E' may be connected by a cord with the stick at the lower end of the shade, as shown in Fig. 1 in dotted lines. 65

My improved attachment permits the raising or lowering of the shade, with its roller, to any desired position on the window, so that the admission of the light can be regulated by closing either the upper or the lower part 70 of the window. This would be of special advantage whenever it is desired to have light and ventilation at the upper part of the window.

My improved attachment can be manufactured at a comparatively small expense, so that it is within the reach of most every one, it forming an accessory to the well-known spring-rollers, which can readily be attached to any window-frame in any required position relative to the window-sashes. 75

Another advantage of my improved attachment is that the well-known rollers of the Hartshorn type can be used without any change directly in connection with my attachment. 85

Having thus described my invention, I claim as new and desire to secure by Letters Patent—

The combination with two grooved guide-rails attached to the window-frame, of a shade-roller, the studs of which are guided in said rails, suspension-plates through which the studs are passed, cords applied to the suspension-plates, said cords being guided over 90 pulleys at the upper part of the window-frame and extending down along and in the grooves of the guide-rails, and means for fastening the suspension-cords after the shade-roller has 95 been adjusted to its proper position on the guide-rails, substantially as set forth. 100

In testimony that I claim the foregoing as my invention I have signed my name in presence of two subscribing witnesses.

MORRIS ECKER.
